UNITED STATES PATENT OFFICE.

EMIL C. G. MUELLER, OF ELIZABETH, NEW JERSEY, ASSIGNOR, BY MESNE ASSIGNMENTS, TO WESTERN ELECTRIC COMPANY, INCORPORATED, A CORPORATION OF NEW YORK.

TRANSMITTER-MOUTHPIECE.

1,242,022.

Specification of Letters Patent.

Patented Oct. 2, 1917.

Application filed April 29, 1915. Serial No. 24,798.

To all whom it may concern:

Be it known that I, EMIL CHARLES GUSTAV MUELLER, a citizen of the United States, residing at Elizabeth, in the county of Union and State of New Jersey, have invented certain new and useful Improvements in Transmitter-Mouthpieces, of which the following is a full, clear, concise, and exact description.

10 This invention relates to transmitter mouthpieces and has for its object the provision of a mouthpiece of a novel and very simple structure.

A mouthpiece made in accordance with 15 this invention is comprised of a body portion made of porcelain or other similar material, and an attaching ring secured in any suitable manner to one end thereof, said ring being provided with prongs adapted to engage 20 projections formed integral with said body portion. Radially disposed sound openings or vents are molded in the edge of the end carrying the attaching ring, said vents coinciding with the spaces between the 25 prongs of the attaching ring to furnish air passages into the sound chamber of the transmitter without the necessity of any drilling operation.

This invention is illustrated in the accompanying drawing in which Figure 1 is a sectional view of a mouthpiece embodying the features of this invention; Figs. 2 and 5 are perspective views of the attaching ring; Fig. 3 is a perspective view of the mouthpiece shown in Fig. 1; Fig. 4 is a sectional view of a modified form; and Fig. 6 is a perspective view of the modified form shown in Fig. 4.

A mouthpiece made in accordance with 40 the invention comprises the usual flaring bell shaped body portion, which is preferably molded from porcelain and provided with the usual perforated partition or grid 2 adjacent the small end thereof. A substantially annular channel 3 is molded in the 45 edge portion of the inner or small end of the mouthpiece. Lugs or projections 4 located in the annulus are provided with radially disposed openings or vents 5 molded 50 therein, which feature will be more fully described hereinafter. In order to removably secure the mouthpiece on the telephone transmitter, there is provided a ferrule or attaching ring 6. A portion 7 of the exterior of

this ferrule is of reduced diameter to form 55 a shoulder or abutment 8 and the entire outer surface is threaded. The reduced portion 7 is bifurcated and the two resulting prongs are adapted to engage the lugs or 60 projections 4, and when the ring or ferrule 6 is secured in position, the interdivisional spaces in the portion 7 coincide with the 65 openings 5 in the end of the body portion 1 to form air relief passages communicating with the sound chamber of the transmitter. 70 This arrangement eliminates the necessity of any drilling operation in providing vents either before or after assembly of the elements 1 and 6, which materially reduces the 75 cost of manufacture of mouthpieces, especially those made from porcelain. Cement is applied to the threads of the reduced portion 7 of the ring 6, and then said ring is inserted into the channel 3 with the spaces between the prongs of portion 7 registering 80 with the openings 5, in which position the shoulder or abutment 8 is in contact with the end of body portion. The binder is allowed to harden, thus securing the ring 6 firmly in position. The screw threads 85 formed upon the reduced portion 7 function as a means for more rigidly holding the ring in place by virtue of the cement engaging said threads when in a plastic condition and afterward setting. The engagement of 90 projections 4 with the two prongs of the reduced portion 7 prevents relative rotation of the body portion 1 and the ring 6 in event the cement becomes loosened. The axial length of the ring 6 is greater than 95 the depth of the recess 3 and when said ring is affixed to the body portion 1, with the shoulder 8 abutting against the end of the 100 said body portion, a portion of said ring will project beyond the inner edge of the mouthpiece, which affords means for attaching the mouthpiece to the transmitter. When the mouthpiece is in operative position, the 105 openings 5 provide relief passages for the air forced out of the sound chamber of the transmitter when said transmitter is actuated.

Figs. 4 and 6 show a modified form of the mouthpiece contemplated by this invention. In this modified form the annular channel 3 is eliminated, leaving the projections 4 standing out prominently. The shoulder 8 of the ring 6 abuts against the end of the body

portion 1 and provides a seating surface for the ring 6. In other respects, this modified mouthpiece is similar to the one described above.

5 From the above, it will be apparent that a mouthpiece embodying the features of this invention will be simple in structure and cheap to manufacture.

What is claimed is:

- 10 1. In a telephone mouthpiece, a body portion, a tubular metallic attaching means therefor having a plurality of projecting members, a base for said body portion provided with a plurality of recesses corresponding in number to the number of said projecting members, and into which said members may be inserted, means on said base intermediate said recesses and coöperating with said members to prevent relative rotation of said body portion and said attaching means, said base also being provided with air vents extending laterally therethrough intermediate said recesses, and
- 15
- 20

means for securing said attaching means to said body portion.

2. In a telephone mouthpiece, a body portion, a tubular metallic attaching means therefor having a plurality of projecting members, a base for said body portion provided with a plurality of recesses corresponding in number to the number of said projecting members and into which said members may be inserted, means on said base intermediate said recess and coöperating with said projecting members to prevent relative rotation of said body portion and said attaching means, said base also being provided with air vents extending laterally therethrough intermediate said recesses, an annular abutment on said attaching means against which the base of said body portion rests, and means for securing said attaching means to said body portion.

In witness whereof, I hereunto subscribe my name this 28th day of April A. D., 1916.

EMIL C. G. MUELLER.
